UNITED STATES PATENT OFFICE.

LEWELL J. GILMAN, CHARLES W. FROST, AND CHARLES H. FOSTER, OF SANTA ROSA, CALIFORNIA.

HARVESTER.

SPECIFICATION forming part of Letters Patent No. 339,761, dated April 13, 1886.

Application filed February 28, 1885. Serial No. 157,383. (No model.)

To all whom it may concern:

Be it known that we, LEWELL J. GILMAN, CHARLES W. FROST, and CHARLES H. FOSTER, of Santa Rosa, Sonoma county, State of California, have invented an Improvement in Harvesters; and we hereby declare the following to be a full, clear, and exact description of the same.

Our invention relates to that class of agricultural machines known, generally, as "harvesters," and in some localities as "headers;" and our invention consists in the novel construction and mounting of the draper-frame or platform and its connection with the main frame, whereby it may be kept always level for any cut, high or low, its limits of motion defined and regulated, and the whole frame evenly balanced; in the novel power-transmitting connections, by which the work of the machine is divided between the two wheels in substantially equal proportions; in the novel manner of adjusting the reel and in the inclination of its cross-bars; and, finally, in the means by which the speed of the reel and the draper is regulated, all of which we shall hereinafter fully explain.

The general object of our invention is to provide an easy-working and readily-handled header adapted to do its work without waste of material or loss of power.

Referring to the accompanying drawings, Figure 1 is a perspective view of our harvester. Fig. 2 is a plan showing the power-transmitting devices. Fig. 3 is a vertical cross-section of the reel, showing the inclined bars V. Fig. 4 is a detail showing the crank-shaft U, for adjusting the reel.

A is the frame-work, supported upon wheels B, which are mounted in the sides of the frame and as nearly central as possible, whereby said frame is nicely balanced. Hinged to the rear of the frame is the push-beam C, having the steering-wheel c, the platform c', and the vertical rack c'', as usual.

D is the main operating-lever, by which the frame A is inclined. This lever is connected with the frame at its forward portion, and is pivoted in a slotted standard, d, on its rear portion, and thence, extending backwardly, engages with the vertical rack c''.

E is the draper-frame or platform, and F is the draper.

G is the sickle-bar, and g is the reciprocating sickle.

In the ordinary machines the draper-frame forms a portion of the front of the main frame, and consequently when said frame is inclined by the operation of the lever the draper-frame is inclined also, and the heads which are cut by the sickle have a tendency to fall forward again from the draper or backward over it. In our machine we have a transverse pivot-shaft, H, extending across the front of the main frame. Upon this shaft the draper-frame is hinged or pivoted, whereby it is adapted to have a rocking movement independent of and adapted to counteract the rocking of the main frame.

Projecting rearwardly from the ends of the draper-frame are side arms, e, which extend to the line of the pivot-axis of the main frame. From the ends of these arms extend uprights e', connected by the cross-bar e'' above the wheels. Projecting rearwardly from the center of this cross-bar is a limiting-arm, I, pivoted to said cross-bar and secured within a slotted standard, J, on the forward portion or cross-bar of the push-beam.

The connection between the arm I and the standard J is an adjustable one, and consists of a series of holes, i, in the arm, and a series, j, in the standard, through which a removable pin or bolt, K, passes, whereby the lever may be shortened horizontally and its point of adjustment varied vertically. The effect of this construction is as follows: When the operating-lever is moved, the rear of the main frame A and the forward end of the push-beam are depressed or elevated, which movement, through the various connections, effects the reverse in the rear of the draper-frame, and raises or lowers it, thus exactly counteracting the inclination of the main frame, whereby the said frame is kept perfectly level, whether for a high or a low cut, and none of the grain is lost. By the adjustment of the arm I the limit of motion through which the draper-frame passes is defined, so that it may be made to cut very high, or be moved down low enough to pass immediately

over the ground. The main frame being nicely balanced on its wheels and the draper-frame being pivoted on a balance and operated from a rear extension lying in the vertical plane of the pivotal axis of the main frame, the whole machine can be handled very easily.

In ordinary machines but one wheel is made to do the driving. This causes great wear and strain upon the machine. Our machine is arranged so that both wheels shall have about an equal portion of work to perform. The left-hand wheel is provided with a gear, Z, upon its axle, which meshes with the pinion z upon a counter shaft, L. This shaft carries on its forward end a crank-wheel, l, to which is connected a pitman, l', the other end of which joins the rear end of a centrally-pivoted lever, l'', which operates the sickle g. Upon the shaft L is also a beveled pinion, m, which meshes with a beveled pinion, m', on a counter-shaft, M, the other end of which carries a cone-pulley, n. From this cone-pulley a belt, N, extends to a cone-pulley, n', on the end of the reel-shaft. It will be observed that the left-hand wheel has therefore the working of the sickle and the reel.

On the axle of the right-hand wheel is a gear, O, which meshes with a pinion, o, on a counter-shaft, P, which carries a chain-pulley, p, from which a chain, Q, extends to a chain-pulley, q, on a counter-shaft, q'. Upon this same shaft is a cone-pulley, r, from which a belt, R, extends to a cone-pulley, r', on the upper drum of the draper in the spout S. This work of driving the draper is considered as about equivalent to the work which the other wheel has to perform.

T is the reel, which is mounted in the forward end of lever t, pivoted on the standards t', extending upwardly from the draper-frame, and having their rear ends connected by links t'' with cranks u on a rock-shaft, U, which is journaled in bearings on the cross-bar e''. The center of this shaft has a crank, u', by which it is rocked or oscillated. By operating the crank the reel can be adjusted nearer to or farther from the ground, as may be desired, and in order to hold it in the position to which it is adjusted we have the arm or lever u'' connected with the crank u', and provided with a series of notches, u'', on the under surface of its rear end, whereby it may engage with a cross-bolt, J', in the top of the slotted standard J on the cross-head of the push-beam, and thus hold the parts.

The cross slats or bars V of the reel, instead of being set in radial planes, as is usually done, are set at a slight angle therewith, so that instead of coming with the flat surface against the grain they work under it with an inclined edge, thereby lifting it better upon the draper.

It will be observed that the pulleys by which the reel is driven are cone-pulleys. The object of this is that by moving or shifting the belt to one side or another by suitable means the reel may be driven at a greater or less speed. When the grain is light and stands

upright, the reel requires to be driven at a slow rate of speed, as all that is necessary is, that it shall incline the grain backwardly over the draper; but when the grain is more or less down the reel requires to be driven very rapidly, as well as to be lowered, whereby the grain is thrown backward onto the draper. For a similar reason the pulleys which drive the draper are also cone-pulleys. When the grain is sparse and dry, the draper can be driven at a slow rate of speed, and thus save wear and tear upon it, and when the grain is heavy and thick it requires to be driven at a high rate of speed for the purpose of preventing it from clogging.

Having thus described our invention, what we claim as new, and desire to secure by Letters Patent, is—

1. In a harvester, the wheeled main frame A, the push-beam C, hinged to its rear, and having standard J on its forward end, and the operating-lever D, by which the frame is inclined, in combination with the draper-frame or platform E, hinged to the forward end of the main frame, and provided with rearwardly-extending arms e, and the adjustable limiting-arm I, pivoted to and adjusted within the standard J, whereby when the rear of the main frame and the front of the tongue are depressed or elevated the front of the draper-frame is lowered or raised to keep said draper-frame on a level, substantially as herein described.

2. In a harvester, the wheeled main frame A, the push-beam C, hinged to its rear, and having the standard J on its forward end, and the operating-lever D, by which the frame is inclined, in combination with the draper-frame or platform E, hinged to the forward end of the main frame, and having rearwardly-extending side arms, e, the uprights e' on said arms, and cross-bar e'' between the uprights, and the limiting-arm I, pivoted in the standard J on the push-beam and on the cross-bar e'', substantially as and for the purpose herein described.

3. In a harvester, the wheeled main frame A, the push-beam C, hinged to its rear, and having the standard J, with a vertical series of holes, j, and the lever D, by which the main frame is inclined, in combination with the draper-frame or platform E, hinged to the forward end of the main frame, and having rearwardly-extending arms e, the uprights e' on said arms, and cross-bar e'' between the uprights, and the limiting-arm I, pivoted on the cross-bar, and having horizontal series of holes i, by which it may be adjustably pivoted in the standard J on the push-beam, substantially as and for the purpose herein described.

4. In a harvester, the main frame A, having wheels B, on which it is balanced fore and aft, the push-beam C, hinged to the rear of the main frame, and having standard J, and the lever D, by which the frame is rocked on its wheels, in combination with the draper-frame or platform E, hinged to the front of the main

frame, and having side arms, e , extending rearwardly to the line of the pivotal axis of the main frame, the uprights e' on said arms, passing upwardly in the plane of said axis, 5 the cross-bar e^2 , connecting the uprights, and the limiting-arm I , pivoted in the standard J and on the cross-bar e^2 , arranged and adapted to operate substantially as herein described.

5. In a harvester, the main frame A , having 10 wheels B , the sickle g , the reel T , and the draper F , in combination with the mechanism by which the sickle and reel are driven, consisting of the gear Z on the axis of one wheel, the pinion z , the counter-shaft L , crank l , pitman 15 l' , pivoted lever l'' , the bevel-pinnions m m' , counter-shaft M , pulleys n n' , and belt N , and the means by which the draper is driven, consisting of the gear O on the axle of the other wheel, the pinion o , counter-shaft P , having 20 chain-pulley p , counter-shaft q' , having chain-pulleys q , the chain Q , the pulleys r r' , and belt R , substantially as and for the purpose herein described.

6. In a harvester, the draper-frame or platform E , as described, having the uprights e' t' 25 and the cross-bar e^2 , in combination with the reel T , and the means by which it is supported vertically adjusted and held, consisting of the levers t , pivoted to the standards t' , and carrying the reel-shaft, the rock-shaft U , journaled 30 on cross-bar e^2 , the links t' , connecting the crank-shaft with the rear ends of the levers t , the notched arm or lever u^2 , connected with shaft U , the standard J on the push-beam, and the cross-bolt j' in said standard, with which 35 the notched arm or lever u^2 engages, substantially as herein described.

In witness whereof we have hereunto set our hands.
